(57) **CLAIM**

The ornamental design for a table with attached chair, as shown and described.

DESCRIPTION

FIG. 1 is a top and front, right side perspective view of a table with attached chair showing our new design according to a first embodiment;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top and front, right side perspective view of a table with attached chair showing our new design according to a second embodiment;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof;

FIG. 14 is a bottom plan view thereof;

FIG. 15 is a top and front perspective view of a table with attached chair showing our new design according to a first embodiment shown in an environment with additional connected tables with attached chairs;

FIG. 16 is a top and front perspective view of a table with attached chair showing our new design according to a first embodiment shown in an environment with additional connected tables with attached chairs;

FIG. 17 is a top and rear, right perspective view of a table with attached chair showing our new design according to a first embodiment shown in an environment with additional connected tables with attached chairs; and,

FIG. 18 is a top and front perspective view of a table with attached chair showing our new design according to a

(Continued)

second embodiment shown in an environment with an additional connected table with attached chairs. The broken lines showing additional tables with attached chairs in FIGS. 15-18 illustrate environment and form no part of the claimed design. The remaining broken lines in the drawings illustrate portions of the table with attached chair that form no part of the claimed design.
